UNITED STATES PATENT OFFICE.

JOHN HOWARD ROSS, OF HANDSWORTH, ENGLAND.

ACETYLENE-GENERATOR.

No. 926,610.

Specification of Letters Patent.

Patented June 29, 1909.

Application filed April 28, 1908. Serial No. 429,721.

To all whom it may concern:

Be it known that I, JOHN HOWARD Ross, subject of the King of Great Britain, residing at 17 Gordon road, Handsworth, Staffordshire, England, have invented certain new and useful Improvements in Acetylene-Generators, of which the following is a specification.

This invention relates to improvements in acetylene generators for lamps and the like, and its object is to provide improved means whereby to maintain, practically, an uniform head of water above the point at which it is fed to the carbid, in order to insure a more uniform pressure and supply of gas to varying requirements.

The primary feature of my invention is, the employment in the manner hereinafter described and shown, of fixed and moving pipes,—of a more or less telescopic character—in connection with the water supply mechanism of such generators, and in which the supply is discharged from the upper part of the moving pipe, the movement of the said pipe being effected by its being connected to, or operated by, a suitable moving part in the generator. I attain this object by the mechanism illustrated in the accompanying drawings, in which:—

Figure 1 shows this my invention as applied to an acetylene generator, in which arrangement the expansible carbid container, is utilized as the means for operating the supply pipe. Fig. 2 shows this my invention as applied to an acetylene generator, in which arrangement a moving float carried at the head of the water is utilized as the means for operating the supply pipe. Fig. 3 shows this my invention as applied to an acetylene generator, in which arrangement a movable gas reservoir is utilized as the means for operating the supply pipe.

Similar numbers of reference apply throughout to the same thing or part.

I do not confine myself to the precise details in carrying out this my invention, inasmuch as it will be readily seen that in each of the cases shown and described some of the details differ from the others, but at the same time it will be seen that the essential feature of my invention, viz., the arrangement and operating of the fixed and moving pipes is alike in each case.

Referring to the arrangement as shown in reference to Fig. 1:—5 is a movable pipe having its lower end closed, said pipe being car-

ried or supported from the interior wall 6^a of the carbid container 6 by means of the flange 7 which is secured to the pipe 5 resting upon the top of the wall 6^a. The upper 65 side 8 of this flange 7 is the point at which the delivery of water to the carbid takes place.

9 is an interior pipe which is of a fixed character, by being secured to the bottom 65 of the water reservoir 10.

11 represents the water which may pass through the holes 12 into the pipe 9 and thence to the pipe 5. The carbid container is supported by the spring 13. 70

14 is the gas reservoir the contents of which may be delivered for consumption through the pipe 15, to the burner 16.

17 is a valve which under the pressure from the spring 18 always tends to close 75 upon and shut off the water from the pipe 9. This valve may be opened and retained open as illustrated, by means of the rod 19 having side projections 20, which may be lowered into the cross recesses 21 (shown in dotted 80 lines) for closing the valve, and raised and turned at right angles so as to rest upon the upper surface 22 in order to open said valve.

The action of this device is therefore as follows:—The height or head of water represented by reference number 23 having been determined according to the intended demand upon the generator, that is to say, when the generator is in working, the normal pressure of the gas will sufficiently resist the inflow of water so as to maintain that head. The valve 17 is opened, when the water will pass down the inner pipe 9 and rise exteriorly thereto in the pipe 5 until it overflows at 8 passing thence to the 95 carbid through the holes 24. Gas is imme-

diately generated which passes into the chamber 14, and at the same time the carbid expands and forces its container downward against the spring 13, and consequently the 100 delivery point 8 is correspondingly lowered, which lowering,—when the apparatus has assumed its proper working—will coincide with the lowering of the water at 11, and thus maintains an uniform height. As before intimated the valve 17 may be closed 105 when the generator is not required. It will further be seen that the valve 17 serves also as a safety valve, inasmuch as should the

gas in the chamber 14 become excessive 110 while the valve 17 is open, it will force back the water and find its way readily to the at-

mosphere through the space between the bush 25 and the rod 19. Even should the valve be shut, the said excessive pressure would raise the valve 17 and permit the escape of the gas. The lower part of the generator is closed by any suitable door or the like 26 secured in any convenient manner.

Referring now to the arrangement as illustrated in Fig. 2, the pipe 5 is connected to the moving float 27 by means of the rod 28 and the yoke 29. The fixed pipe 9 is secured to the bottom 10 of the water reservoir by means of the upstanding cylinder 30. The water shut off valve in this case is shown at 31, controlling the inlet thereto to the interior of the fixed pipe 9. This valve can be opened or closed by the screwed end 32. The action in this case is briefly as follows:— The head of water 23 is arranged as before described. The valve 31 is opened, and the water passes as before down the pipe 9 and thence up the pipe 5, and over its end 8, flowing therefrom to the carbid through holes 24. As the water level at 11 is lowered, so also is the float 27 lowered, and with it of course the overflow point 8 of the pipe 5, thus maintaining an uniform head of water pressure.

It will also be here noticed that in case of excessive gas pressure, the water will be driven back through the pipes 5 and 9 as before described, and escape through the top of the latter.

Referring now to Fig. 3, it will be seen that substantially the same arrangement exists as in the two previous cases except as to the moving body utilized to operate the pipe 5. In this case the pipe 9 is secured to the upright cylinder 30 which is part of the water reservoir 10, and whose upper end is closed except at the central opening of the pipe 9. 33 is the gas holder, its interior forming the gas chamber 14. The pipe 5 is connected to the end stop 34, between which and the top of the cylinder 30 is disposed the spring 35, which tends always to close the upper end of the pipe 5 against the interior of the cylinder 30, or the bottom against the lower end of the pipe 9 to act as a valve, and thus completely shut off the water supply. In this case the carbid container 6 is conveniently made to pass horizontally into position through the doorway at the side when the door 26^a is removed. Its action is therefore as follows:—The height or head of water is arranged as before described. To initially start the apparatus the tap 15 is opened, when the withdrawal of gas (if there is any in the holder) permits the said holder 33 to descend until the stop 34 is slightly depressed by the top of the holder 33, by which the upper end or point 8 of pipe 5 is lowered so that the water can pass thence to the carbid, when gas is generated and passes into the chamber 14. So long as the gas is at or below the normal pressure, the holder 33 rests

on and controls the stop 34, by which the end 8 of the pipe 5 is maintained at the predetermined height, and as the water at 11 is lowered so also the holder 33 is lowered and the point 8 is correspondingly lowered. Should however the pressure in the chamber 14 be increased beyond demand, or the tap 15 closed, the holder will rise and leave the stop 34, so that the spring 35 will then lift the pipe 5, and thus cut off the supply of water. Further, in case the pressure in chamber 14 becomes excessive the lower end of the inverted pipe 36 will be raised above the upper end of the pipe 37, when the gas will at once freely escape through said pipe to the atmosphere without further raising the holder.

What I claim as my invention and desire to secure by Letters Patent is:—

1. In an acetylene generator, in combination, a water supply reservoir, a carbid container and a gas chamber receiving gas from the carbid container, a pipe fixedly related to the reservoir, a second pipe surrounding the fixed pipe, discharging at its upper end into the carbid container, and having its lower end closed, and means for causing the downward movement of the second pipe to lower the discharge point of the water in proportion to the lowering of the level of the water in the reservoir.

2. In an acetylene gas generator, in combination, a water supply reservoir, a carbid container and a gas chamber receiving gas from the carbid container, a fixed pipe into which the water from the reservoir flows, an axially movable pipe closed at its lower end and surrounding the fixed pipe, the movable pipe discharging water into the carbid chamber at a point below the level of the water in the reservoir and means whereby the movable pipe and therewith the discharge point of the water is lowered in proportion to the lowering of the level of the water in the reservoir.

3. In an acetylene gas generator, in combination, a water supply reservoir having a fixed discharge pipe, a carbid container and a gas chamber receiving gas from the carbid container, a movable pipe telescopically related to the fixed pipe and arranged to discharge water into the carbid container at a point below the level of the water in the reservoir and means whereby the movable pipe and therewith the discharge point of the water is lowered in proportion to the lowering of the level of the water in the reservoir.

4. In an acetylene gas generator, in combination, a water supply reservoir having a fixed discharge pipe, a carbid container and a gas chamber receiving gas from the carbid container, a movable pipe transferring water from the fixed pipe to the carbid container and discharging at a point below the level of the water in the reservoir, and means where-

by the movable pipe and therewith the discharge point of the water is lowered in proportion to the lowering of the level of the water in the reservoir.

5. In an acetylene gas generator, in combination, a water supply reservoir, a carbid container, and a gas chamber receiving gas from the carbid container, means causing the discharge of water into the carbid container from the reservoir at a point below the level of the water in the latter, means for lowering the discharge point of the water in proportion to the lowering of the level of the water in the reservoir and a pipe in the water chamber and opening to the atmosphere, the pipe being normally sealed and serving to relieve excess pressure due to overgeneration when such excess pressure attains a degree sufficient to overcome the action of the sealing means.

6. In an acetylene gas generator, in combination, a water supply reservoir having a depending fixed pipe, a movable carbid container spaced from the reservoir to provide

for a gas chamber, a pipe supported by the carbid container surrounding the fixed pipe and having a closed lower end and means yieldably supporting the carbid container.

7. In an acetylene gas generator, in combination, a water supply reservoir, a fixed discharge pipe leading therefrom, a carbid container and a gas chamber receiving gas from the carbid container, a pipe movably related to the fixed pipe and transferring water therefrom to the carbid container, means whereby the movable pipe and therewith the discharge point of the water is lowered in proportion to the lowering of the level of the water in the reservoir, and a spring pressed valve controlling the admission of water to the fixed pipe.

In testimony whereof I have hereunto set my hand in presence of two subscribing witnesses.

JOHN HOWARD ROSS.
